ATTORNEY

UNITED STATES PATENT OFFICE.

LOUIS P. VALIQUET, OF NEW YORK, N. Y., ASSIGNOR TO LOUISA LAWRENCE,
OF SAME PLACE.

PERFORATOR.

SPECIFICATION forming part of Letters Patent No. 436,048, dated September 9, 1890.

Application filed June 17, 1890. Serial No. 355,783. (No model.)

To all whom it may concern:

Be it known that I, LOUIS P. VALIQUET, a citizen of the United States, and a resident of New York city, in the county of New York 5 and State of New York, have invented certain and useful Improvements in Perforators, of which the following is a specification.

The object of my invention is to provide a small, cheap, durable, and powerful punch 10 or perforator; and to this end my invention consists in the features of construction and combinations of devices hereinafter more fully described, and particularly pointed out in the appended claims.

15 In the accompanying drawings, Figure 1 is a plan view of a punch or perforator embodying my improvements, the upper plate and handle being turned back. Fig. 2 is an edge view of the same and showing also in 20 dotted lines the relation of the parts during the perforating or punching operation. Fig. 3 is a top view of the combined handle and upper die-plate. Fig. 4 is a similar view of the lower die-plate. Fig. 5 is a vertical section taken at the line $x-x$ of Fig. 1.

In the several views the same part will be found designated by the same numeral of reference.

1 represents a base-plate having perforations 2, by which the contrivance may be screwed upon a board or tablet 2. Formed integral with the base-plate at the front and flaring outwardly are two ears or lugs 4, each of which is provided with a punching-die 5. 30 At each end of the base-plate is formed an upright 6, having a horizontal perforation 7 and a vertical wall or face 8. The perforations are directly opposite each other and the vertical walls are arranged in line.

40 9 designates a cross-bar of a length sufficient to just fit between the inner faces of the uprights 6, and formed at each end with a threaded hole 10 to receive the threaded end of a screw 11, which is provided with a 45 plain cylindrical portion 12. The plain portions 12 of the screws are arranged to occupy the plain perforations 7 in the uprights and form journals for the cross-bar. Formed integral with the cross-bar is a forwardly-extending handle 14 and two arms 15, each pro-

vided with a perforation 16. The arms extend laterally beyond the ends of the cross-bar and forwardly, so that the perforations 16 register with the punching-dies in the base-plate. The punching-dies are provided 55 each with a rubber sleeve 17 to act as a stripper.

In the operation of the contrivance the handle and the arms 15 are raised, and the letter-sheet or bill or other paper is passed 60 over the tops of the dies until its edge abuts against the two vertical walls 8 of the uprights. The handle and the arms are then turned down to the dotted-line position shown at Fig. 2, and the studs, coacting with the 65 holes 16, caused to punch or cut out two circular disks from the paper. The handle and the arms are then raised and the paper removed and placed upon the wires of a letter or bill file, if desired. The contrivance is 70 adapted to be fastened to the tail end of a letter or bill file tablet, and when thus applied the handle portion may be swung back, as shown at Fig. 2 in full lines, to bear upon the free ends of the sheets and hold them 75 down in position.

By the oblique or flaring arrangement of the lugs or ears 4 and the arms 15 I am enabled to set the punching devices farther apart than would be possible if the arms were 80 arranged at right angles to the cross-bar. The vertical walls or faces 8 of the uprights 6 serve as stops or gages for the top edges of the sheets of paper to be punched, and hence all of the sheets may be perforated at the 85 same distance from said edge and be arranged evenly on the upright wires or tubes of a file or binder. By reason of the capacity of the handle and arms to be turned back through almost one hundred and eighty degrees the insertion and gaging of the sheets to be perforated may be most conveniently accomplished. As the handle is made comparatively long and the cutting or punching performed quite close to the fulcrum or center 90 of movement of the handle or lever, a contrivance of considerable power is produced. By pivoting the cross-bar or head of the handle closely between the two uprights the arms 95 15 are prevented from moving laterally and 100

changing the relationship or altering the alignment between the perforations 16 and the studs or dies 5, which alignment, it will be understood, must be always carefully preserved to insure proper working of the contrivance. There may of course be as many studs or dies and complementary perforations as desired, and without departing from my invention the dies may be upon the arms 15 and the perforations in the base-plate, though I prefer the plan illustrated.

What I claim as new, and desire to secure by Letters Patent, is—

1. In a perforator, the combination of a base-plate having two uprights, a cross-bar arranged between and pivoted to said uprights, an operating-handle, and die-carrying arms, the handle and the arms being made integral with said cross-bar, as set forth.
2. The combination, with a base-plate having studs or dies and two uprights provided

with journal-bearings, of a cross-bar threaded at each end and arranged between said uprights, the screws engaging with the cross-bar and having plain journal-like portions resting in the bearings in the uprights, and the perforated arms and operating-handle made integral with the cross-bar, as set forth. 25

3. The combination, with a base-plate having flaring ears or lugs provided with studs or dies and two uprights provided with journal-bearings, of a lever arranged between and pivoted to said uprights and having obliquely-arranged arms provided with holes to co-operate with the studs or dies, as set forth. 30

Signed at New York city, in the county of New York and State of New York, this 14th day of June, A. D. 1890.

LOUIS P. VALIQUET.
